[57] CLAIM

The ornamental design for a mirrored medicine cabinet, as shown and described.

DESCRIPTION

FIG. 1 is a top, front, and left side perspective view of a first

embodiment of a mirrored medicine cabinet showing my new design;

FIG. 2 is a front elevational view of a second embodiment thereof, the only difference residing in the width of the cabinet;

FIG. 3 is a right side elevational view thereof, the left side being a mirror image of that shown;

FIG. 4 is a top plan view thereof;

FIG. 5 is a bottom plan view thereof;

FIG. 6 is an enlarged, fragmentary cross-sectional view thereof, taken along line 6—6 of FIG. 2;

FIG. 7 is an enlarged, fragmentary cross-sectional view thereof, taken along line 7—7 of FIG. 2;

FIG. 8 is an enlarged partial front elevational view of the top portion of the first embodiment thereof;

FIG. 9 is a further enlarged partial front elevational view of the center detail of the top portion thereof; and,

FIG. 10 is a further enlarged, fragmentary cross-sectional view thereof, taken along line 10—10 of FIG. 9.

The undisclosed rear surface is plain and unornamented.
